GOLF BALL WASHING MACHINE

Application filed October 4, 1929. Serial No. 397,237.

This invention relates to improvements in golf ball washing machines. Golf balls have their peripheral portions painted or otherwise coated with a substantially white color. In the course of the game the balls become soiled by contact with the ground, through grass stains, by contact with the clubs, handling and other causes. Players therefore desire from time to time to remove such soil stains, as far as practicable, from the surfaces of the ball to keep the latter in its desired whitened condition. Machines have been employed heretofore for this purpose, and it is a primary object of the invention to provide a new and improved machine which will overcome the objections present in the machines heretofore proposed for this purpose, and it is another object of the invention to provide a machine of simple and improved construction, capable of imparting extended service with minimum repair and attention and also to construct the machine so that all surfaces of a golf ball placed therein will be thoroughly scrubbed by the action of a pair of spaced stationary brushes positioned in substantially vertical planes wherein the bristles of the brushes are presented to the surfaces of the ball in such manner as to effectually remove soil stains to the end of restoring the ball as far as practicable to its original color.

For a further understanding of the invention reference is to be had to the following description and the accompanying drawing, wherein:

Figure 1 is a vertical longitudinal sectional view taken through the ball cleaning machine comprising the present invention, the lid or cover of the machine being shown in its fully open position,

Figure 2 is a transverse sectional view taken through the machine on the plane indicated by the line 2-2 of Figure 1,

Figure 3 is a perspective view showing the rotatable ball carrier.

Referring more particularly to the drawing, the numeral 1 designates the improved golf ball cleaning machine comprising the present invention in its entirety. The machine consists of a cubical metallic casing 2 wherein is provided spaced vertical side walls 3-3, a bottom wall 4, vertical end walls 5-5 and an open top. One of the end walls 5 terminates at its upper end in an eye 6 through which passes a hinged pintle 7, the latter being employed to pivotally unite the metallic lid or cover 8 of the casing to the stationary base structure. The opposite end of the cover 8 is provided with a spring catch 9 which is adapted to engage with an offset lip 10 projecting from one of the end walls 5.

The interior of the base portion of the casing is provided with a plurality of block sections 11 which are so united as to produce therebetween a substantially circular chamber 12. In fact, the chamber 12 is truly circular when the cover 8 is closed and the block section 11 which is carried by the inner wall of the cover assumes an operative position in the casing.

Secured to the inner surface of the side walls 3-3 are brushes which consist of back portions 13 and horizontally projecting bristles 14. The bristles of these brushes are relatively spaced and terminate substantially evenly with the side walls of the block sections 11, but the distance between these brushes is less than the diameter of the balls to be cleaned, as shown in Figure 2. This is done in order that the balls will be brought into proper frictional rubbing engagement with the brush bristles.

In order to provide for improved contact between the golf balls and the cleaning surface of the brush bristles, there is provided, in lieu of the usual sliding type of carrier, a rotatable carrier. This carrier, as shown in Figure 3, comprises a hub 15 which is mounted upon a shaft 16 journaled in bearings 17 formed in connection with the side

walls 3—3. The shaft 16 is equipped exteriorly of the casing, with a crank handle 18 by which it may be grasped and manually rotated in order to effect the rotation of the carrier. The hub 15 of the carrier is provided with radiating dowel pins 19 which are preferably rounded and fit at their inner ends in sockets formed radially in the hub 15. The outer ends of the pins 19 are preferably decreased in diameter and rounded as indicated at 20.

In operation water or a soap solution, as indicated at 21, is placed in the casing the lid or cover being in the open position disclosed in Figure 1. A golf ball or balls to be cleaned is then forced downwardly by manual pressure into engagement with the pins of the carrier, the said pins being spaced apart a sufficient distance to loosely receive but one ball therebetween. It will be observed that there is a pair of brushes connected with each of the side walls 3 and each pair of these brushes are relatively spaced to produce a vertical groove permitting the golf ball to be forced downwardly in an easily executed manner into engagement with the pins 19. The cover is then swung to a closed position and locked through the spring catch 9, and the carrier is revolved by the manual actuation of the handle 18. Due to the circular formation of the walls of the chamber 12 the balls are confined within the limits of said chamber and are positively retained in frictional engagement with the strong bristles of the cleaning brushes. The balls while being revolved in the carrier rotate in all directions, so that all portions of the surfaces of the balls will be rapidly engaged by the bristles, insuring a thorough and effective cleaning of the ball surfaces to the end of removing soil stains and restoring the original whiteness of said surfaces. When the cover is opened continued rotation of the carrier causes the balls to be automatically ejected from engagement with the bristles. This is secured by the rounded ends 20 of the pins 19 which serve, as soon as the ball is removed from engagement with the circular walls of the chamber 12, to project the balls outwardly and radially.

In view of the foregoing it will be seen that the present invention provides a simple and improved machine for effecting the operation of cleaning golf balls and other similar spherical objects. The invention involves but few parts, is not likely to get out of order and requires but little attention to keep the same in a proper operating condition.

60 What is claimed is:

A golf ball cleaning machine comprising a casing including a removable closure, a partition wall positioned within said casing and formed, when said closure occupies a casing closing position, to provide a substantially

circular opening, brushes carried by the walls of said casing and projecting toward said opening, a rotatable carrier positioned within said opening and provided with radially extending fingers between which golf balls are adapted to be positioned, and means admitting of manual rotation of said carrier to bring the golf balls carried thereby into frictional rubbing engagement with the bristles of said brushes.

In testimony whereof we affix our signatures.

STARLING S. WILCOX, Jr.
HARVEY R. GREINER.
